MULTIPLE CEMENT BLOCK FORMING MACHINE AND METHOD OF MAKING HOLLOW BUILDING BLOCKS

Elie Owen Blackwell, Gainesville, Fla.

Application May 10, 1937, Serial No. 141,802

7 Claims. (Cl. 25—41)

This invention relates to machines for molding hollow concrete building blocks and has for its object to provide a comparatively simple and thoroughly efficient machine of this character, by means of which a plurality of hollow building blocks of any desired size and shape may be constructed at each operation of the machine.

A further object of the invention is to provide a block-forming machine in which the outer walls or segments of the blocks are preformed and subsequently united to the connecting webs to form an integral homogeneous block.

A further object is to provide a multiple block machine, the web-forming cores of which are provided with transverse cutting knives which engage the cement constituting the side walls of the molded product and serve to sever or divide said product into individual blocks of uniform size and shape.

20 A further object is to provide a block-forming machine comprising a supporting frame having side forms pivotally mounted thereon and normally disposed in a horizontal plane to permit the ready introduction and convenient tamping 25 of cement therein to form continuous preformed side walls, said side forms being adapted to be swung upwardly in contact with the web-forming cores so that, when cement is introduced between the cores and in contact with the pre-30 formed side walls, the connecting webs will be intimately united to and bonded with the side walls of the block and when the cores are withdrawn from the molding chamber the knives on the core will cut or sever the molded product into individual blocks.

35 A further object is to provide a block-forming machine, the construction of which is such as to permit the formation of a moisture-proof hollow concrete block having outer veneer faces of relatively fine material and inner faces and connecting webs of relatively coarse material whereby the cost of construction is materially decreased.

A still further object of the invention is generally to improve this class of machine so as to increase their utility, durability and efficiency.

In the accompanying drawings forming a part of this specification and in which similar numerals of reference indicates corresponding parts in all the figures of the drawings:

Figure 1 is a perspective view of a multiple block-forming machine embodying the present invention showing the side members of the molding chamber in horizontal position for preforming the side walls of the building block,

Figure 2 is a top plan view of Figure 1.

Figure 3 is a transverse sectional view taken on the line 3—3 of Figure 2.

Figure 4 is a similar view showing the pre-formed side walls of the block in vertical position preparatory to introducing the cement in the web-forming spaces of the core.

Figure 5 is a transverse sectional view showing the core in lowered position to release the molded product and effect severance thereof into individual blocks of uniform length, and

Figure 6 is a perspective view of a set of building blocks made by the machine.

The improved machine forming the subject-matter of the present invention is particularly designed for making two or more hollow concrete blocks of the type shown in Figure 6 of the drawings. That is to say, hollow blocks of any desired size and shape in which the opposite side walls thereof are united by integral connecting webs to permit free circulation of air therethrough when the block is laid into a wall or other structure.

The machine comprises a supporting frame or table 5 having side extensions 6 and provided with depending supporting legs 7. Mounted on the supporting table 5 is a pallet 8 on which is mounted a vertically movable web-forming core 9. The web-forming core 9 consists of a plurality of sections 10 of any desired shape and spaced apart to form intermediate web-forming recesses 11 preferably disposed at an angle to each other, as shown. Each core section 10 is preferably stamped or otherwise formed from sheet metal and the interior of each core section 10 is filled with cement 12 and allowed to harden so as to impart the desired strength and stability to the core. Certain of the core sections 10 are provided with transverse knives 13 embedded in the cement 12 and having their ends projecting laterally beyond the opposite sides of the sections and provided with cutting edges 14 for the purpose hereinafter referred to. Secured to the bottom of the pallet 8 is a block or plunger 14' slidably mounted between suitable depending guide members 15 and connected through the medium of a bolt 16 with an operating lever 17. The operating lever 17 is pivotally mounted, at 18, on a bracket 19 secured to one of the supporting legs and connected with the end of said lever is a foot or hand operated device of any desired construction for the purpose of raising and lowering the core.

Pivots mounted, at 21, on the table 5 are the side members 22 of a molding chamber, in-

dicated at 23, and these side members are normally supported in a horizontal position on the table 5, as best shown in Figure 3 of the drawings. The side members 22 comprise spaced 5 longitudinal side strips 24 and 25 defining an intermediate molding cavity 26 adapted to receive a quantity of cement to permit preforming of the side walls of the concrete block; that is to say, before the side walls are joined or united 10 by the connecting webs. Secured to the opposite ends of the table 5 are stationary end plates 27 having openings 28 formed therein to permit the attachment of inclined braces 29, the purpose of which are to hold the side members 22 in 15 vertical position at opposite sides of the molding chamber 23 after the side walls of the block have been preformed. End plates 30 are pivotally mounted, at 31, on the extensions 6 of the supporting table, and these end plates 30 are adapt- 20 ed to be swung upwardly to form end closures for the molding chamber 23, as will be readily understood. Secured to the outer faces of the side members 22 are vertical braces 32 for the purpose of reinforcing and strengthening said mem- 25 bers and the lower ends of these braces are pivotally mounted on the pivot rod 21 so that they will swing with the side members downwardly in engagement with the supporting table. The upper surface of the supporting table is prefer- 30 ably provided with transverse seating grooves 33 adapted to receive the braces 32 when the side members are in lowered position and thus permit the lower surfaces of the side members to rest flat against the supporting table and pro- 35 vide a firm foundation during the tamping of the concrete within the molding cavities 26.

In operation, the side members 22 are moved to a horizontal position in engagement with the upper surface of the supporting table 5, after 40 which cement or other suitable plastic material 34 is shoveled or otherwise introduced within the molding cavities 26 and thoroughly tamped to preform the side walls of the building block. The side members 22 carrying the preformed cement 45 side walls are then swung upwardly on the pivot rod 21 to a vertical position to form the side walls of the molding chamber, after which the end plates 30 are swung upwardly to close the end walls of said molding chamber, the parts 50 being secured in this position by the braces 29. Cement is then introduced within the web forming passages 11 and thoroughly tamped so as to cause the moistened cement to adhere to the moist surfaces of the preformed side walls 34 55 and thus become intimately united and bonded thereto. After the web-forming recesses or spaces 11 have been entirely filled with cement and the connecting webs joined with the preformed side walls 34, the lever 17 is actuated to lower or 60 drop the core 9. As the core 9 drops, the cutting edges 14 of the knives 13 will pass through the preformed side walls 14 and sever or cut the molded product into a plurality of individual blocks 35 of uniform shape and dimensions. By 65 reference to Figure 6 of the drawings, it will be noted that these blocks 35 consist of spaced side walls united by integral connecting webs 37, and these connecting webs 37 may be either straight or disposed at an angle to each other, the pur- 70 pose being to provide a moisture-proof block having openings therein to permit the free circulation of air through the blocks when said blocks are laid into a wall. After the core has been dropped, the molded blocks are allowed to remain 75 in position until the cement has thoroughly set

or solidified, after which the braces are removed and the side members swung downwardly on their pivot 21 to lowered or horizontal position, thus permitting the blocks to be conveniently removed from the machine and deposited in a suitable place for future use. 5

If it is desired to mold the blocks with colored or veneered outer faces, a cement mixture of the desired color is first poured into the molding cavities 26, after which ordinary cement is placed 10 thereon and thoroughly tamped. When the blocks are formed in this manner, the outer faces of the blocks will be of relatively fine material while the inner faces of the blocks and connecting webs may be made of relatively coarse material, thereby materially reducing the cost of manufacture. Both the inside and outside walls of the block may be so veneered, thereby eliminating the plastering of walls on the inside of a building or of stuccoing on the outside where a moisture-proof block is used. This coloring or veneering of the outer faces of the block also eliminates the necessity of coloring the entire aggregate which is very expensive. 20

As the side walls are preformed while in a horizontal position, said walls may be constructed with greater facility and more rapidly and with better results than if the side walls were formed in the main molding chamber at the same time the connecting webs were formed. Moreover, 25 with the present machine any desired number of blocks may be formed at one time, the number of blocks being formed depending upon the length of the molding chamber 23 and the location of the cutting knives 33, as will be readily understood. 30

It will, of course, be understood that the machines may be made in different sizes and shapes and constructed to permit the simultaneous formation of any desired number of building blocks 40 at one operation of the machine. 45

From the foregoing description, it is thought that the construction and operation of the machine will be readily understood by those skilled in the art and further description thereof is deemed unnecessary. 50

Having thus described the invention, what is claimed as new is:

1. The method of making hollow building blocks which consists in providing vertically disposed cores spaced from each other, disposing open 55 faced molds in a substantially horizontal position at opposite sides of the cores, filling the molds with plastic material, shifting the molds to an upright position against opposite sides of the cores while the material is still in a plastic condition, filling space between the cores with plastic material, allowing the plastic material in the molds and between the cores to unite and set to form side walls of a block and webs extending between the side walls and bonded thereto, removing the cores and the molds, and allowing the formed block to thoroughly dry and harden. 60

2. The method of making hollow building blocks which consists in providing open faced molds spaced from each other, disposing cores between the molds in spaced relation to each other, filling the molds with plastic material, moving the molds into position to dispose their open faces into contact with opposite sides of the cores and the plastic material therein across spaces between the cores, filling space between cores with plastic material and allowing the plastic material in the molds and between the cores to unite and set to 65 form side walls of a block and cross webs bonded 70

at their ends to the side walls, and removing the cores and the molds.

3. The method of making hollow building blocks which consists in providing open faced molds spaced from each other and movable from a horizontal position to a vertical position, disposing cores between the molds in spaced relation to each other while the molds are in a horizontal position, filling the horizontally disposed molds with plastic material to form side walls of a block and moving the filled molds to a vertical position against opposite sides of the cores with portions of the plastic material exposed between the cores, filling spaces between the cores with plastic material to form webs having their ends integrally bonded to the preformed side walls, cutting the side walls between certain of the webs while in a plastic condition to divide the block into a plurality of small blocks, and removing the small blocks.

4. The method of making hollow building blocks which consists in disposing open molds horizontally in spaced relation to each other, filling the molds with cement to form side walls of a block, positioning web-forming cores between the molds and providing certain of said cores with cutting knives, moving the filled molds to a vertical position in contact with opposite sides of the cores, introducing cement between the cores to form connecting webs, tamping the material between the cores to intimately unite said material with the material constituting the preformed side walls and form a homogeneous structure, withdrawing the cores from between the molds and causing the knives carried thereby to cut through side walls of the block and divide the block into individual blocks of uniform size and returning the molds to a horizontal position.

5. The method of making hollow building blocks which consists in providing a molding apparatus having pivoted side walls normally disposed in a horizontal plane and provided with molding cavities, introducing cement within the molding cavities while the side walls are in a horizontal plane to produce preformed side walls of a block, positioning web-forming cores between the pivoted side walls, moving the side walls upwardly to a

vertical position against opposite sides of the web-forming cores while the cement is in a plastic condition, introducing cement between said cores and in contact with the preformed side walls to cause the plastic material constituting the webs and preformed side walls to be intimately united and bonded together to form a homogeneous integral block when set, and removing the formed block.

6. A machine for making hollow concrete building blocks comprising a frame, side molds carried by the frame and movable from a horizontal position to a vertical position, web-forming cores mounted for vertical movement between the side molds, said molds constituting means for pre-forming the opposite side walls of a block when in a horizontal position, means for supporting said side molds against opposite sides of the cores whereby when cement is introduced between said cores the resultant connecting webs will be integrally united with said preformed walls, and means carried by the cores for severing the side walls of the block and dividing the block into predetermined lengths when the cores are withdrawn from between the side molds.

7. A machine for making hollow building blocks comprising a table, pivoted side molds carried by said table for movement from a horizontal position to a vertical position and forming the side walls of a molding chamber when in a vertical position and provided with molding cavities for preforming the side walls of a block when in a horizontal position, web-forming cores movable vertically between the side molds, some of said cores being provided with cutting knives projecting from their sides, end walls for the molding chamber pivotally mounted on the table, means for supporting the pivoted side molds and end walls in upright position whereby when concrete is introduced between the cores the resultant connecting webs will be integrally united with said preformed walls to form an integral product, and means for retracting the cores from between the side molds to cause the cutting knives to pass through the side walls of the block and sever the molded product into predetermined lengths.

ELIE OWEN BLACKWELL.
